FOLDING CHECK BOOK COVER

Milton A. Heinzelman, Webster Groves, Mo.

Application November 4, 1937, Serial No. 172,727

5 Claims. (Cl. 281—19)

This invention relates to folding cases or covers, particularly folding pocket check book covers. The object of the invention is to produce a neat, serviceable, compact and easily foldable cover at low cost. The invention consists in the folding cover hereinafter described and claimed.

In the accompanying drawing, which forms part of this specification and wherein like symbols refer to like parts wherever they occur,

10 Fig. 1 represents a blank suitable for the manufacture of a one-piece pocket folding check book cover;

15 Fig. 2 is a view showing the endmost side flaps on one side of the blank folded upon the middle section thereof;

Fig. 3 is a view showing the flap on the other side of the blank folded upon the two folded end side flaps and said middle section;

20 Fig. 4 is a view showing the intermediate side flap folded upon the slotted side flap, with the edges of the folded blank sewed together and with the end portions thereof provided with the spring stud and socket members, respectively, of a snap fastener to form the finished cover;

25 Fig. 5 is a longitudinal section through the finished cover on the line 5—5 in Fig. 4;

Fig. 6 is an inside view of the cover with the pass book and check pad mounted therein;

30 Fig. 7 is a side view of the closure flap side of the folded cover; and

Fig. 8 is an enlarged fragmentary section through the folded cover on the line 8—8 in Fig. 7.

35 My folding check book cover is formed from a rectangular one-piece blank of leather or other foldable material which is scored or creased along two parallel longitudinal lines 1 and 1a, respectively, and slit along two parallel transverse lines 2, forming a middle portion or section 3 with a single flap 4 extending along one side from end to end thereof and a relatively long intermediate flap 5 and two relatively short end flaps 6 and 7, respectively, on the opposite side thereof. As shown in the drawing, the blank has two elongated slots or slits 8 and 9 cut therein transversely thereof, the slot 8 being located in the side flap 4 adjacent to the transverse center line thereof and the slot 9 being located in the end side flap 6 close to slit 2 that separates said flap from the intermediate side flap 5. The endmost side flaps 6 and 7 preferably terminate short of the outer side edge of the intermediate side flap 5; and the side flap 4 has a shallow notch 10 in the outer side edge thereof disposed opposite to 55 and of the same length as said intermediate side

flap. At the ends of the blank, the middle section 3 and the side flaps 4, 6 and 7 are provided with rounded corners, all having the same radius of curvature. The blank is preferably die-cut and scored in one operation.

5 The two end side flaps 4 and 5 of the blank thus formed are folded along the longitudinal folding line 1 flat upon the middle section 3 (see Fig. 2). The long opposite side flap 4 is then folded along the folding line 1a flatwise upon the 10 folded end side flaps 4 and 5 and said middle section 3 (see Fig. 3). The intermediate side flap 5 is then folded flatwise upon the side folded flap 4, after which the overlapped side flaps are secured together and to the middle section 3 by 15 a line of stitching 11, the corners of the folded blank are rounded and the spring stud and socket members 12 and 13 of a snap fastener are secured to the respective end portions of said folded blank to form the completed cover (see Fig. 4). 20

25 The intermediate side flap 5 is located on the inner face of the cover and cooperates with the slotted side flap 4 to form a longitudinal tunnel or passageway in said cover 14 that terminates short of the ends thereof. One end of this passageway forms a pocket for a pass book 15 and the other end of said passageway is adapted to receive the anchoring tab 16a of a check pad 16. The pass book end of the cover is adapted to be doubled or folded down on the intermediate portion thereof along a line located opposite the transverse slot 8, and the other end of said cover is adapted to be folded over the adjacent free end of the folded pass book containing portion of said cover and secured thereto by the cooperating 30 socket and spring stud members of the snap fastener.

35 The principal advantages of the foregoing folding pocket case or check book cover are its one-piece construction, its strength and durability, and the flexibility imparted thereto along its transverse lines of folding due to the material removed along said line by the slots 8 and 9 in the intermediate ply of the three-ply cover. Straight side edges are provided along the side 40 edges of the cover by reason of the notch 10 in the outer side edge of the main side flap 4 and by making the folded end side flaps 6 and 7 terminate short of the line 1a along which said main flap is folded. Obviously, the article hereinbefore described admits of considerable variation without departing from my invention, and I do not wish to be restricted to the details disclosed.

45 What I claim is:

50 1. A folding check book cover made from a 55

- one-piece blank with opposite side flaps, one extending the full length of said blank and the other terminating short of both ends thereof, said side flaps being folded one over the other 5 over the middle portion of said blank and permanently secured together and to said middle portion adjacent to their lines of folding, the short side flap overlapping the full length side flap and cooperating therewith to form a longitudinal 10 open-ended passageway in said cover that terminates short of the ends thereof and is adapted to receive at one end the anchoring end of a check pad and at the other end a pass book, the underlying full length folded side flap having an elongated slot therein that extends along the line 15 on which said cover is folded to pocket size and is covered by said middle portion and the overlapping short length folded side flap.
2. A folding check book cover made from a one-piece blank comprising a middle section having a single full length flap along one side thereof and end and intermediate flaps along the opposite side thereof, the end side flaps being folded over the end portions of said middle section, the single full length side flap being folded over said middle section and said folded end side flaps and the intermediate side flap being folded over said single full length side flap, said folded side flaps being secured to said middle section adjacent to their lines of folding and said folded intermediate side flap cooperating with said folded single full length side flap to form an open-ended passageway that terminates short of the ends of the cover and is adapted to receive at one end the anchoring end of a check pad and at the other end a pass book.
3. A folding check book cover made from a one-piece blank comprising a middle section having a single full length flap along one side thereof and end and intermediate flaps along the opposite side thereof, the end side flaps being folded over the end portions of said middle section, the single full length side flap being folded over said middle section and said folded end side flaps and the intermediate side flap being folded over said single full length side flap, said folded side flaps being secured to said middle section adjacent to their lines of folding and said folded intermediate side flap cooperating with said folded single full length side flap to form an open-ended passageway that terminates short of the ends of the cover and is adapted to receive at one end the anchoring end of a check pad and at the other end a pass book, said cover being adapted to be folded to pocket size along a line located intermediate between the ends of said passageway.

intermediate between said ends of said passageway, and said folded single full length side flap having an elongated slot therein that extends along such line of folding.

4. A folding check book cover made from a one-piece blank comprising a middle section having a single full length flap along one side thereof and end and intermediate flaps along the opposite side thereof, the end side flaps being folded over the end portions of said middle section, the single full length side flap being folded over said middle section and said folded end side flaps and the intermediate side flap being folded over said single full length side flap, said folded side flaps being secured to said middle section adjacent to their lines of folding and said folded intermediate side flap cooperating with said folded single full length side flap to form an open-ended passageway that terminates short of the ends of the cover and is adapted to receive at one end the anchoring end of a check pad and at the other end a pass book, said cover being adapted to be folded to pocket size along a line located intermediate between said ends of said passageway and along a line located between one end of said passageway and the corresponding end of said cover, said folded single full length side flap having an elongated slot therein that extends along said first mentioned line of folding, and the end side flap located at said second line of folding having an elongated slot therein that extends along such line of folding.

5. A folding pocket case made from a one-piece blank comprising a middle section having a single full length flap along one side thereof and a relatively long intermediate flap and two relatively short end flaps along the opposite side thereof, the end side flaps being folded over the end portions of said middle section, the single full length side flap being folded over said middle section and said folded end side flaps and the intermediate side flap being folded over said single full length side flap, said folded side flaps being secured to said middle section adjacent to their lines of folding and said folded intermediate side flap cooperating with said folded single full length side flap to form an open-ended passageway that terminates short of the ends of said case, said case being adapted to be folded to pocket size along two transverse lines, one located intermediate between the ends of said open-ended passageway and the other between one end of said passageway and the corresponding end of said case.
